LUBRICATING DEVICE FOR SHAFTS AND
CAR WHEEL JOURNAL AXLES

Ernest Armstrong, West Collingwood, N. J.

Application September 23, 1933, Serial No. 690,660

2 Claims. (Cl. 308—87)

This invention relates to lubricating devices for shafts and car wheel journal axles.

For lubricating the shaft or axle within a journal box, various forms of wick supporting, lubricating devices have been used to bring up oil by wick to the running shaft or axle, from an oil reservoir or cavity, within the journal box. In the case of car wheel journal boxes, in common use, the problem of properly supporting the wick is a difficult one to solve effectually, reliably and cheaply, owing to the restricted space in which to position the holding member for supporting the wick in a proper position. Wick holding means are required which must at all times maintain the functioning position of the wick for bringing oil up to the shaft, or axle, and at the same time the holding means must have all its parts as free as possible from the wearing and destructive effects of the vibration and pounding which the journal box and associated parts, as the bearing brass and the overlying wedge member, are subjected to. The wedge member transfers the superimposed weight of the supported car, during the running of the train, directly to the bearing brass, on the axle. My experience with different kinds of wick supporting devices, as parts of lubricating means, for car wheel journals, has led me to observe the destructive effects of vibrations and pounding between the wedge member and the bearing brass upon any part of a wick supporting member held between them. Once the wick drops out of contact with the running axle or shaft, the bearing suffers from the loss of oil.

It is therefore the main object of my invention to provide a form of wick supporting means as part of a lubricating device for a journal box and its shaft or axle, as is adapted to fit where it will be least affected by any pounding or vibration, and at the same time be held from being dislodged from its proper wick supporting position, and particularly in the case of use for car wheel journals, to be adapted to have its upper parts occupy and hang from certain restricted spaces available beyond the ends of the wedge member as it rests directly upon the bearing brass, so that, while the upper parts of the wick supporting means hang on the bearing brass, these parts do not come between the wedge member and the bearing brass, and are therefore free from any pounding that attends the superimposed weight of the car between the wedge and the brass. The engagement of these upper parts of the wick supporting member with the said re-

stricted spaces holds these parts from dislodgement therefrom, when once so assembled.

Another object of my invention is to provide a strong and durable wick holder, which I call a cradle frame, which will fulfill the above named object, having its upper parts fit into the said restricted spaces, so as to hold the cradle frame in position to properly support a wick and preferably be made of a tough metal for cheapness, strength and durability, and at the same time have reinforced parts for longer wear.

With these and other objects, which will herein-after appear, my invention resides in certain construction, one embodiment of which is illustrated in the drawing in connection with a car wheel journal box. The device is described in detail, its functions and operation are explained, and what I claim is set forth.

In the drawing,

Figure 1 is a perspective view of the lubricating device, embodying my invention, showing the cradle frame and wick pads attached.

Figure 2 is a vertical axial section of a journal box and axle, including one form of my lubricating device mounted therein.

Figure 3 is a vertical section taken on the line 3—3 of Figure 2.

Figure 4 is a perspective view of the top bearing brass, of the journal shown in Figure 2.

In the figures, the journal box 10 is shown to have the usual inclined cover 11, with the car wheel axle 12, the dust guard 13, the oil cavity 14, the top bearing brass 15, and the wedge 16. Fitting over and around the sides of the bearing brass 15, is the cradle frame 17, of the lubricating device 18. The cradle frame 17 is preferably made of heavy tough wire, formed with upstanding ends 19 and 20, each formed as an inverted U in shape, and each shaped to fit the upper contour of the respective end of the bearing brass 15, over which it lays. It will be observed that the end 19 is polygonal, having a straight top part 21, inclined side parts 22 and vertical parts 23, adapted to lay over and fit the upper prismatic surface of the bearing brass 15. Welded to the top part 21, is a reinforcing member 24, serving to strengthen the top part against wear. The end 20 is curved, fitting the upper curved surface of the rear end lip 25, of the bearing brass 15. It will be observed that the ends 19 and 20, of the cradle frame 17, will be free from any pinching or superimposed weight passing down thru the wedge 16 into the bearing brass 15. Integral with the lower extremities of the frame ends 19 and 20 are the bar portions 26

and 21, of the cradle frame 17. While any form of wick can be hung from the bar portions 26 and 27, of the cradle frame 17, I prefer to use the fabric sheet wick 28, having a loop 29, within the oil cavity 14, which has side portions 30 and 31, with pads 32 and 33, at the upper parts of the respective side portions 30 and 31. These pads 32 and 33 are formed by a long pile 34, woven with the wick, like the heavy pile 10 of a thick Wilton carpet, having the pile 34 contacting the side surfaces of the axle 12. The wick 28 is preferably made narrower in width than the spacing between the frame ends 19 and 20. The bar portions 26 and 27 come directly below the 15 longitudinal lugs 35, of the bearing brass 15, so as to hold these bar portions 26 and 27 from jumping up, while the ends 19 and 20 hold the frame 17 in hanging position at the restricted spaces beyond the wedge 16 and over the ends of the bearing 20 brass 15. The end 20, of the frame 17, has an upwardly bent portion 36 and a reinforcing bar 37, welded thereto. The portion 36, with its bar 37, occupies the restricted space 38, between the prismatic end of the bearing brass 15 and the top 25 wall of the journal box 10, so as to effectively hold in place the upper part of this end 19, of frame 17. The curved end 20 lies over the lip 25, and is beneath the extending lug members 40, and is thus held against vertical displacement. Inasmuch 30 as the body of the wedge 16 is between the ends 19 and 20, of the cradle frame 17, this frame is held in position against end displacement. The bar portions 26 and 27 of the frame 17 are located alongside the running surface of the axle 12, to 35 be a little above a horizontal plane passing through the axis of the axle 12. The wick 28, hanging from these bar portions 26 and 27, has its respective side portions 30 and 31 looped around the respective bar portions 26 and 27, and riveted together at 39, to be fixed thereon. It 40 will be noticed in Figure 3, that the pads 32 and 33 lay against, and partly around, the running surface of the axle 12, above the horizontal line 55, passing through the axis, of the axle 12, while 45 below this line, the pads with the wick, hang straight down until the U-portion of the wick is reached.

Any particles of dirt, grit or metal, lodging in the pile 34, of the pads 32 and 33, will have 50 opportunity to shake loose therefrom during the vibration, attending the running of the axle 12, on account of the upright position of the pads 32 and 33, which lightly contact the running surface of the axle 12. While the particles of dirt, grit 55 and metal will gravitate into the oil cavity 14, at the loop 29, the oil is drawn up by the wick 28, and

will naturally be filtered, bringing only clean oil to the running surface of the axle 12.

The frame ends 19 and 20, having their upper portions occupying restricted places over the ends of the bearing brass 15, beyond the contacting area of the wedge 16 with the bearing brass 15, are there held from dislodgement from these restricted places, and at the same time are free from the pounding area between the wedge 16 and the bearing brass 15. 10

Modifications of the above described and here-with illustrated embodiment of my invention, including an adaptation for shafting, can be made without departing from the spirit and scope of said invention. I therefore wish to include all 15 forms of pad lubricators which come within the purview of the following claims.

I claim:—

1. Within a car wheel journal box, having an oil cavity, an axle of a car wheel, a bearing member upon said axle and a wedge member mounted upon said bearing member, a lubricating device comprising a wire holding means and a wick, said wire holding means including a wire member holding said wick against said axle, said wick connecting with said oil cavity, spaced upstanding wire ends to said last named member, hanging upon the ends of said bearing member, with said wedge member between said ends, said wire member being free from the bearing contact area of 30 said wedge member and said bearing member, and reinforcing pieces integral with said upstanding ends, at their upper parts, to prolong the wear of said ends.

2. A lubricating device within a car wheel journal box, having also within the said box, an axle of a car wheel, a bearing member resting upon the said axle, a wedge member, having a bearing contact area with said bearing member, shorter than said bearing member, and on top of the same, and 40 there being an oil cavity below said axle within said box, said lubricating device including a wick reaching down into said cavity, and wick holding means supported by hanging upon the ends of bearing member, said wick holding means comprising two spaced end members, positioned upon said bearing member to hang across the ends of said bearing member to be out of the said bearing area and free from pressure from said wedge member, to have said wedge member between said 50 end members, and a wick supporting member integral with the depending ends of said end members, and positioned to support said wick against said axle.

ERNEST ARMSTRONG. 55
